UNITED STATES PATENT OFFICE.

LEONHARD BAUMEISTER, OF ERLANGEN, GERMANY, ASSIGNOR TO KNY-SCHEERER COMPANY, OF NEW YORK, N. Y.

MERCURY-CONTACT BREAKER.

1,000,320.

Specification of Letters Patent. Patented Aug. 8, 1911.

Application filed November 12, 1910. Serial No. 591,979.

To all whom it may concern:

Be it known that I, LEONHARD BAUMEISTER, a subject of the Emperor of Germany, residing at Erlangen, Bavaria, Germany, engineer, have invented certain new and useful improvements in Mercury-Contact Breakers, of which the following is a specification.

This invention relates to a mercury contact breaker, and has for its object to utilize 10 the heating effect of the spark which is produced when the contact is broken to effect a rapid separation between the contact point and the surface of the mercury, and thus a rapid extinction of the spark. For this purpose a gas or steam-blast is formed at the 15 end of the contact pin when it leaves the mercury by the action of the spark on an extinguishing fluid floating on the surface of the mercury.

According to the present invention the contact is inclosed by a bell or chamber which is closed at the bottom by the mercury, and prevents the gas or vapor, which is generated by the action of the spark on 20 the extinguishing fluid from expanding upward, so that the pressure of the gas or vapor is caused to act downward on the surface of the mercury situated at the point of interruption, and the mercury is suddenly 25 forced downward by the generated gas or vapor, whereby the spark produced on the breaking of the contact is rapidly extinguished, and thus a complete interruption 30 of the circuit insured, even when the contact pin is raised relatively slowly.

One form of such a contact-breaker is illustrated in the drawing, Figure 1 being a vertical section thereof. Figs. 2, 3 and 4 detail views showing different positions of 35 the contact pin.

As shown, the contact pin 1 extends downward into a chamber 2, which is closed at the top by means of a lid 8 having a downwardly projecting portion 9, said portion 9 being provided at its lower end with a bell 4 that extends half-way into the mercury 3. The contact pin is arranged within portion 9, and a recess 10 is formed in said portion 9 whereby part of the length of the contact 50 pin is exposed.

In order to enable the contact pin 1 to be actuated from the outside, the contact pin is carried relatively tightly through a passage 5 provided in the top of the hollow chamber. The contact pin can be moved

by means of a solenoid 6, which acts in the manner of an automatic interrupter on the iron core 7 furnished with the contact pin 1. When the contact pin is raised through the action of the solenoid 6 to such an extent that it quite leaves the mercury (Fig. 2) the heat of the spark formed at the point of interruption acting on the extinguishing liquid, alcohol for example, generates enough gas to produce a relatively high 60 pressure. As the chamber 2 is closed at the top and only the mercury situated below is displaceable, the latter is suddenly forced downward by the gas pressure (see Fig. 3), so that in this way a rapid interruption of 70 the current is effected.

For the purpose of removing the gas pressure, and restoring the normal level of the mercury, the contact-pin 1 is moved upward at each interruption to such an extent that 75 it opens the passage 5 (Fig. 4).

In order to further accelerate the interruption a plurality of contact pins may be arranged so that the points at which they break contact are circuitized in series.

What I claim and desire to secure by Letters Patent is:—

1. A contact breaker comprising, in combination, a receptacle, a layer of electrical conducting liquid disposed therein, a contact member adapted to make and break contact with said liquid, a bell disposed over said liquid in which said contact member works, a liquid disposed within said bell adapted to expand when a spark is created 85 by the breaking of the contact between said conducting liquid and said contact member and to force said conducting liquid away from said contact member, and means for feeding said liquid to within said bell. 90

2. A contact breaker comprising, in combination, a receptacle, a layer of electrical conducting liquid disposed therein, a contact member adapted to make and break contact with said liquid, a bell disposed over 100 said liquid in which said contact member works, and a layer of liquid disposed over said conducting liquid and within said bell adapted to expand when a spark is created by the breaking of the contact between said conducting fluid and said contact member, and to force said electrical conducting liquid away from said contact member. 105

3. A mercury contact breaker comprising, in combination, a receptacle, a layer of mer- 110

cury disposed therein, a contact member adapted to make and break contact with said mercury, a bell disposed over said mercury and in which said contact member works, and a layer of fluid disposed above said mercury and within said bell adapted to expand when a spark is created by the breaking of the contact between said mercury and said contact member and to force 10 said mercury away from said contact member.

4. A mercury contact breaker comprising, in combination, a receptacle, a layer of mercury disposed therein, a contact member 15 adapted to make and break contact with said mercury, a bell disposed over said mercury and in which said contact member works, a layer of liquid disposed above said mercury and within said bell adapted to vaporize when a spark is created by the breaking of the contact between said mercury and said contact member and to force said mercury away from said contact member, and means for periodically admitting a quantity 20 of said liquid within said bell.

5. A mercury contact breaker comprising, in combination, a receptacle, a layer of mercury disposed therein, a contact member to make and break contact with said mercury, 30 means for actuating said contact member, a layer of fluid disposed over said mercury, means for inclosing a portion of said fluid and within which said contact member

works, the inclosed fluid being adapted to expand when a spark is created between the 35 contact member and said mercury, and a passage for establishing communication between said inclosed fluid and the fluid without said inclosing means.

6. A mercury contact breaker comprising, 40 in combination, a receptacle, a layer of mercury disposed therein, a lid for said receptacle provided with a downwardly projecting portion said portion having a laterally disposed recess, a bell at the lower end of 45 said projecting portion, a contact member arranged in said projecting portion for making and breaking contact with said mercury within said bell, a layer of fluid disposed over said mercury and within said bell, the inclosed fluid in said bell being adapted to expand when a spark is created therein and to force said mercury away from said contact member, a passageway between said lateral recess and said bell establishing communication between said inclosed fluid and the fluid without said bell, and means for actuating said contact member.

In testimony whereof I have affixed my 60 signature, in presence of two witnesses.

LEONHARD BAUMEISTER.
